UNITED STATES PATENT OFFICE.

SAMUEL A. COMER, OF SHERMAN, TEXAS.

LIFE-SAVING RAFT.

1,123,174.

Specification of Letters Patent. Patented Dec. 29, 1914.

Application filed July 11, 1914. Serial No. 850,415.

To all whom it may concern:

Be it known that I, SAMUEL A. COMER, a citizen of the United States, residing at Sherman, in the county of Grayson and State of Texas, have invented certain new and useful Improvements in Life-Saving Rafts, of which the following is a specification.

This invention pertains to life saving rafts of that class adapted for use at sea, and relates particularly to mechanism adapting it to be stored in desired quantities on board vessels, at life-saving stations, or at other desirable points where such devices are liable to be needed.

In the construction of life-rafts as heretofore it is customary to unite two or more hollow air-tight cylinders spaced some distance apart, by a frame work which maintains them in a plane side by side, depending on these cylinders only for the buoyancy of the raft.

It is an object of my invention to utilize this space between the cylinders also as air-tight compartments, thus attaining the maximum buoyancy of a raft with a minimum weight and size of the structure.

With the above and other objects in view, my invention consists in certain novel constructions, combinations, and arrangements of parts to be hereinafter more fully described, claimed, and illustrated in the accompanying drawings, in which—

Figure 1. is a longitudinal plan view, Fig. 2 is a side view, Fig. 3 is an end view, Fig. 4 is an end view, Fig. 4 is a perspective view of a portion of the cylinders, and Fig. 5 is a transverse sectional view on the line X X of Fig. 2.

Referring more specifically to the drawings in which similar reference characters designate corresponding parts throughout the several views, 1 designates cylindrical metallic floats of suitable diameter and length according to the desired size of the raft. Three or more of them are spaced apart and connected side by side by metal yokes 2 passing around and between them, said yokes being clamped together by bolts 3 and 4. Top and bottom coverings 5 and 6 of sheet metal extend over all the cylinders and the whole length thereof, to which they are secured, and the ends being closed the spaces 7 between the cylinders are converted into floats of greater buoyancy than

is attained by the cylinders. The covers 5 and 6 also extend over the sides of the outer cylinders where the space between them is closed by metal sheets 8 and the ends are closed by sheets 9, forming air chambers 10 which again adds to the buoyancy of the raft. Still other floats 11, triangular in cross section are provided, they extend all around the raft and carry metal lugs 12 that are bolted to floor supports 13 retaining them in place. The ends of all the triangular floats are mitered as shown at 14. The cylinders 1, the spaces 7 between them, and the floats 11 are respectively divided into compartments by the partitions 15—16— and 17, indicated in dotted lines in Fig. 1. The floor supports 13 extend transversely across the top and bottom sides of the cylinders 1 and are secured thereto by the bolts 3. Floors 18 are attached to them in the usual manner, and to both the floors, near the outer sides and ends are secured posts 19 that carry railings 20 which form complete rectangular inclosures. To the posts are also attached life lines 21, provided with floats 22 as shown, so that whichever side of the raft may be in the water these lines will be in readiness to be seized by any person coming near the raft. To the posts 23, secured to the raft, a flag-staff 24 flying a distress signal may be secured by the bolt 25, it is adapted to be folded down upon the floor of the raft when not in use and when needed, raised to a vertical position and secured by a pin through the apertures 26. Also when desired, rowlocks and oars may be provided.

From the foregoing preferred embodiment of my invention it is apparent that I produce a simple and very efficient device, but in attaining these ends I do not wish to be limited to the precise details of construction and arrangement of parts herein set forth, inasmuch as minor changes in the form, proportion, and exact manner of assemblage of the parts may be resorted to without departing from the spirit of my invention or sacrificing any of the advantages of the same.

Having thus described my invention, what I claim and desire to secure by Letters Patent of the United States is—

A life saving raft comprising cylindrical metal floats spaced apart and connected side by side by metal yokes, a top and bottom

metal covering connecting the cylinders forming air chambers between them, and triangular metal floats extending all around the outer sides and ends of the cylinders adjacent thereto and adapted to be connected with the raft, substantially as set forth.

In testimony whereof I affix my signature in presence of two witnesses.

SAMUEL A. COMER.
